CHARGING MACHINE

Ferdinand H. H. Foss, Chicago, Ill.

Application October 27, 1937, Serial No. 171,293

8 Claims. (Cl. 64—29)

This invention relates to charging machines as used in connection with charging open-hearth furnaces and, more particularly, to a means for driving the charging arm of same.

5 Charging machines are now universally used for depositing the materials of the charge from the charging boxes into open-hearth furnaces. There are several types of these machines in use, but the ones most generally used are those 10 of the low ground type. Such machines usually consist of a bottom truck mounted on flanged wheels which are adapted to travel on a very wide gauge track laid in front of the charging sides of furnaces. These trucks carry a charging carriage which is adapted to move on a track carried by the frame of the truck at right angles to the direction of motion thereof; that is, toward and away from the furnaces. This charging carriage carries a long heavy charging arm or ram which extends toward the furnaces and is shaped at its outer end to fit into a socket carried by the charging boxes. The charging boxes which carry the solid material to be charged 15 usually delivered by and rest on buggies which are adapted to run on a narrow gauge track between the charging machine and the furnaces and along the line thereof.

In operation, the truck carrying the charging 20 machine is moved so that the charging arm is directly opposite the charging box to be emptied, and the carriage is then moved forward to bring into position the end of the charging bar, which is then dropped into a socket on the charging box and locked therein. The charging arm is assumed to be opposite the furnace to be charged, and is then raised, together with the charging box, and by a forward motion of the carriage, the charging box and the end of the 25 charging bar are passed into the furnace where, by rotating the charging arm, the box is turned upside down and its contents deposited therein. By reversing these motions, the box is then placed upon a buggy and the next box emptied, as described, until the furnace is fully charged.

45 Such machines have proven very practical in use and have contributed much to the success of the open-hearth method, but they require considerable maintenance due to their construction and the rough treatment that they usually receive in operation, especially the charging arms of the machines. This is primarily due to the fact that when the charging arm is lowered for engagement with the socket of the charging boxes, or when the charging boxes are placed in 50 the furnaces, the charging arm is forced down with such a tremendous force into the socket or against the top of the furnace door as to result in a tremendous shock to the entire charging machine, and often times breakage of the charg-

ing arm, which is, of course, costly and inconvenient.

It is one of the objects of this invention to eliminate the trouble as heretofore described.

It is another object to provide an improved means for driving the arm of a charging machine which will allow the driving means to continue to move in a forward direction in case the charging arm is arrested in its downward movement.

Various other objects and advantages of my 10 invention will more fully appear during the course of the following specification and will be particularly pointed out in the appended claims.

In the accompanying drawings I have shown, for the purpose of illustration, one embodiment 15 of which my invention may assume in practice.

In these drawings:

Figure 1 is a side elevation of a charging machine in which my invention is incorporated;

Figure 2 is a plan of the same machine;

Figure 3 is an end view of the improved ratchet gear mechanism;

Figure 4 is a sectional view taken on line IV—IV of Figure 3; and,

Figure 5 is a sectional view taken on line V—V 25 of Figure 4.

It is generally known how charging machines operate, but it is thought advisable to briefly describe the operation of a particular type of charging machine with which my invention may be incorporated. This machine has a hoisting motor 2 adapted to drive a set of gears in the transmission 3 positioned on one side of the charging carriage, as shown in Figure 2. Connected to the transmission is the driven shaft 4 which drives the gear 5 located in the transmission housing 6, which is located substantially in the center of the carriage which, in turn, drives a larger gear 7 located and journaled therein. Connected to the shaft of the gear 7 and driven thereby are the bell-crank 8 located on each side thereof which are connected to the yoke-end 9 of the charging arm 10 by means of the links 11. The charging arm is pivotally connected to yoke portion 12 of the charging carriage 13 in order to raise and lower the arm and carries on its outer end a connecting portion 14 which is adapted to engage a socket portion 15 in one of a series of charging boxes 16.

According to the present invention, there is 50 provided an intermediate ratchet gear mechanism 17 which is preferably mounted in the gear train of the transmission 3 on the end of the shaft 4. This ratchet gear mechanism includes a ring gear 18 having conventional gear teeth 55 19 on the periphery thereof and a radially extending inner web portion 20 with the radial teeth 21 carried thereby and on one side thereof.

There is mounted inside the ring gear on one side of the web portion a disk 22 having a liner 60

- 23, preferably made of bronze metal arranged around the periphery thereof, which is adapted to lie next to the inside surface of the ring gear. Positioned on the opposite side of the web portion 5 there is a second disk member 24 having a similar liner 25 arranged around the periphery thereof and a plurality of annularly positioned spaced stud bolts 26 carried thereby and extending therefrom toward and through the disk 22. The disk 22 has provided on its inner face, radial teeth 27 similar to the teeth 21 on the web portion of the gear but oppositely disposed and which are adapted to cooperate therewith. The disk 22 also has a plurality of annularly positioned spaced housing portions 28 which are adapted to house the coil springs 29. The stud bolts 26 of the second disk 24 are adapted to extend through the housings of the first disk 22 into engagement with the coil springs 29 to hold 10 the two disks and the teeth of the web of the gear and disk in yieldable engagement. The stud bolts 26 carry washers 30 and nuts 31 for the compression adjustment of the coil springs 29. The disk 22 is keyed to the second disk by means 15 of a key 32 and has a sliding fit therewith, and the second disk 24, in turn, is securely keyed to the main shaft 4 by means of keys 33.

The radial teeth of both the web portion 20 of the ring gear and of the disk 22 are of a distinctive shape, having surfaces 34, which are preferably perpendicular to the plane of the disk, and the web of the gear, top-face portions 35 which are in a plane parallel to the disk and web, and inclined rear surfaces 36.

35 To fully understand the function of the ratchet gear mechanism of my invention, the charging arm is operated in the following manner:

The hoisting motor 2 is energized, which, through the action of the gear train in the transmission 3, tends to rotate the ring gear 18 of the ratchet mechanism 17. The inclined surfaces 36 of the teeth 21 on the web portion of the driven ring gear 18, through the action of the springs 29, engage with the similar surfaces on the teeth 40 27 of the disk 22 turning the shaft 4 which, 45 through the mechanism as heretofore described, drives the charging arm 10 in the lowering direction. When direction of motor rotation is reversed surfaces 34 of ring gear 18 engage with 50 similar surfaces on teeth 27 of the disk 22 turning shaft 4 which, through the mechanism as heretofore described, positively drives the charging arm 10 in the hoisting direction. After the end of the 55 charging arm rises to the proper position and reaches the end of its upward travel above the box 16 to be charged, the direction of hoist motor rotation is reversed and drives the arm downward until the shaped outer end of the arm is brought 60 into engagement with the socket 15 of the charging box 16. The arm carrying the box is then raised and the charge deposited in the furnace as heretofore described. During each cycle of 65 operation, movement of cranks 8 are limited to one half revolution or 180 degrees and force of motor torque is maintained against surfaces 34 on teeth 21 and 27 when hoisting and surfaces 36 when lowering. In case of an overload, when lowering, the inclined surfaces of the teeth on the gear tend to slip over the inclined surfaces of 70 the teeth on the disk. This slipping action, of course, is governed by the size and strength of the coil springs 29.

It is important that these coil springs 29 have sufficient strength to maintain the inclined teeth 75 surfaces 36 in engagement with each other

against the action of a suitable percentage of the hoisting motor full-load torque. Such value should be sufficient to drive the arm downward under all conditions and, at the same time, of such value as to allow slippage of the gear relative to the disks when the arm is incidentally fouled and prevented from moving downward to prevent shock, damage and breakage to the parts of the charging machine.

As a result of this invention, it will be noted that when the torque of a hoisting motor driving the arm downward exceeds the designated value of the force of the springs, the force urging the inclined surfaces to slide over each other then exceeds the compression force of the springs to keep the inclined surfaces 36 of the teeth in engagement and the springs undergo such compression that disks move away from each other and the inclined teeth surfaces of the web of the ring gear and the disk are no longer maintained in engagement, and the radial teeth of the driven ring gear merely slide or ratchet over the corresponding teeth of the disk without engaging or moving the latter and, consequently, without further driving action being exerted to the shaft 4 and 20 charging arm.

While I have, in this application, specifically shown and described an embodiment of my invention, it will be understood that this is merely for the purpose of illustration and description, 30 and that various other forms may be devised within the scope of my invention, as defined in the appended claims.

I claim:

1. The combination with a driven shaft, of a 35 driving ring gear having a radially extending inner web portion, a series of uniformly spaced teeth arranged around one side of said web portion, a disk member positioned on the same side of said web portion of said gear, said disk having a 40 series of similarly shaped teeth on the inner opposed surface thereof which are adapted to cooperate with the teeth on said web portion, a second disk positioned on the opposite side of said web portion, said second disk being keyed to 45 said shaft, a plurality of annular positioned housing portions carried by said first named disk, a coil spring positioned in each of said housings, and a similar number of stud bolts carried by said second named disk member and extending there- 50 through, said springs in said housings to hold said disks together in yieldable engagement with said web portion of said ring gear, said driven ring gear through the action of the teeth thereon adapted to drive said shaft positively in one direction when the ring gear is driven in one direction and yieldably in the opposite direction when the ring gear is driven in the opposite direction.

2. The combination with a driven shaft, of a 60 driving ring gear having a radially extending inner web portion, a series of uniformly spaced teeth carried by said web portion, shaft driving means carried by and connected to said shaft which is adapted to cooperate with the web portion of said ring gear, means for holding said shaft driving means and said web portion yieldably in engagement with each other, and means carried by said shaft driving means with which the teeth on said web portion are adapted to cooperate so as to drive said driving means together with the shaft to which it is connected positively in one direction when the ring gear is driven in one direction and yieldably in the opposite direction when the ring gear is driven in the opposite direction.

3. The combination with a driven shaft, of a driving ring gear having an inwardly extending flange portion, an annularly arranged row of teeth carried by said flange portion, an annular disk member arranged on and connected to said driven shaft, means for holding said disk member and the flange portion of said ring gear yieldably in engagement with each other, and means carried by said disk member with which said teeth on the flange portion of said ring gear are adapted to cooperate so as to drive the disk together with the shaft to which it is connected positively in one direction when the ring gear is driven in one direction and yieldably in the opposite direction when the ring gear is driven in the opposite direction.
4. In a charging machine having a charging arm and a gear train for driving said arm, a ratchet gear mechanism included in said gear train, said mechanism including, in combination, a driven ring gear having a radially extending inner web portion arranged therearound, a plurality of teeth arranged on at least one side of said web portion, a disk member positioned inside of said ring gear on one side of said web portion having a similar number of teeth on the inner surface thereof which are adapted to cooperate with the teeth on said web portion, a second disk member positioned inside of said ring gear on the opposite side of said web portion, and means for yieldably connecting said disks together in engagement with said web portion so that the teeth thereon are normally engaged with the teeth on said first mentioned disk, said driven ring gear through the action of said teeth thereon adapted to drive the first mentioned disk and the second mentioned disk together with the shaft to which the latter is connected so that said charging arm is moved positively in its upward movement when the ring gear is driven in one direction and which will drive the same so that the charging arm is moved yieldably in its downward movement when the ring gear is driven in the opposite direction.
5. In a charging machine having a charging arm, a gear train and a shaft for driving said arm, a ratchet gear mechanism mounted adjacent one end of said shaft in said gear train, said mechanism including, in combination, a driven ring gear having a radially extending inner web portion, a series of teeth arranged around one side of said web portion, a disk member positioned on the same side of said web portion of said ring gear, said disk having a series of similarly shaped teeth arranged on the inner opposed surface thereof which are adapted to cooperate with the teeth on said web portion, a second disk positioned on the opposite side of said web and which is keyed to said shaft, and means including a plurality of springs for holding said disks in yieldable engagement with the web portion of said ring gear so that the teeth on both said web portion and said disk are normally held in yieldable engagement with each other, said driven ring gear through the action of said teeth thereon adapted to drive the first mentioned disk and the second mentioned disk together with the shaft to which the latter is connected so that the charging arm is moved positively in its upward movement when the ring gear is driven in one direction and yieldably in its downward movement when the ring gear is driven in the opposite direction.
6. The combination with a driven shaft, of a driving ring gear having a radially extending inner web portion, a series of teeth arranged on one side of said web portion, a disk member positioned on the same side of said web portion of said gear, said disk having a series of similarly shaped teeth arranged on the inner surface thereof which are adapted to cooperate with the teeth of said web portion, a second disk positioned on the opposite side of said web portion of said gear, said second disk being keyed to said shaft, and means for holding the disks together and in yieldable engagement with said web portion so that the teeth thereon are normally engaged with the teeth on said first mentioned disk, said driven ring gear through the action of said teeth thereon adapted to drive the first mentioned disk and the second mentioned disk together with the shaft to which the latter is connected positively in one direction when the ring gear is driven in one direction and yieldably in the opposite direction when the ring gear is driven in the opposite direction.
7. The combination with a driven shaft, of a driving ring gear having a radially extending inner web portion, a series of teeth arranged around one side of said web portion, a disk member connected to said shaft, a series of similarly shaped teeth arranged around the inner opposed surface of said disk member, and means for holding the disk in yieldable engagement with said web portion so that the teeth thereon are normally engaged with the teeth on said disk member, said driven ring gear through the action of said teeth adapted to drive the disk together with the shaft to which it is connected positively in one direction when the ring gear is driven in one direction and yieldably in the opposite direction when the ring gear is driven in the opposite direction.
8. In a charging machine having a charging arm, a gear train and shaft for driving said arm, a ratchet gear mechanism arranged in said gear train, said mechanism including, in combination, a driven ring gear having a radially extending inner web portion, a series of teeth arranged around at least one side of said web portion, a driven disk member positioned inside of said ring gear on one side of said web portion having a series of teeth arranged around one surface thereof which are adapted to cooperate with the teeth of said web portion, a second disk portion positioned inside of said ring gear on the opposite side of said web and which is securely attached to said shaft, and means for yieldably connecting said disks together comprising a plurality of projecting stud bolts carried by one of said disks and annularly positioned therearound, each of said bolts adapted to extend through and cooperate with a coil spring positioned in a plurality of housings carried by the other of said disk members which are annularly positioned therearound to hold said disks in normally yieldable engagement with each other and with the web portion of the ring gear, said ring gear through the action of said teeth adapted to drive both of said disk portions together with said shaft positively in one direction when the ring gear is driven in one direction and yieldably in the opposite direction when the ring gear is driven in the opposite direction.
